BRASSIÈRE

Anne Alt, Compton, Calif.

Application March 24, 1945, Serial No. 584,601

5 Claims. (Cl. 2-42)

1

This invention relates to brassières and has for an object the provision of a brassière wherein both breast pockets may be cut from a single pattern and easily fashioned into breast supporting form.

A specific object of the invention is to provide a brassière which will effectively hold the breasts in position with a minimum of fabric used.

Whereas at the present time it is customary in the manufacture of brassières to provide such fabric members as a body encircling band, which is normally tightly positioned below the breasts, and pocket portions stitched or otherwise secured thereto, the present invention by its construction provides support without the necessity of utilizing a separate body encircling band.

Another object of the invention is the provision of a brassière incorporating a novel breast pocket construction which while firmly holding the breast or breasts likewise is capable of expansion to accommodate any fullness of the breast.

Another object is the provision in a brassière of a breast pocket construction formed from a single fabric member and so fashioned as to allow maximum firm support beneath the breast while permitting ease in breast support.

Another object is the provision of a brassière construction so constructed that the shoulder straps do not cut or otherwise abrade the shoulders.

Another object is the provision of a brassière which readily accommodates and holds firmly different sized breasts, in that the breast pocket is permitted limited expansion at a certain zone thereof.

Another object of the present invention is to provide a brassière the breast pockets of which are so formed as to have maximum strength at the zone of support, and wherein the breast pocket fabric is capable of stretching transversely at a zone above the medial line of said pocket.

In the drawing:

Fig. 1 is a perspective view of the brassière;

Fig. 2 is a fragmentary view of the brassière looking inwardly of the breast pockets;

Fig. 3 is a pattern form for a breast pocket; and,

Fig. 4 is a fragmentary view of the pattern form of Fig. 3 showing how portions of the fabric may be overlapped prior to sewing.

Referring now to the drawings:

The brassière includes two sections 1 and 2 which are united by seaming along the center line at 3. Each section includes a breast pocket 4 and a back portion 5 seamed thereto, as indicated

2

at 6. The back portions are adapted to be adjustably connected together by means of snaps or hooks and eyes, as indicated at 7 and 8.

The breast pocket construction is such as to permit ready manufacture, and each pocket is formed from a pattern of the general character depicted in plan in Fig. 3. As shown in Fig. 3 the fabric for the breast pocket may be substantially irregular in outline, although it may be circular. The irregularity in outline in the present instance depends on the appearance of the breast pocket when finished. Assuming the outline for the pocket to be that shown in Fig. 3, I divide the pattern into four zones, 9, 10, 11 and 12, the zones being separated by the dotted lines 13 and 14. The dotted line 14 substantially divides the pattern vertically, while the dotted line 13 divides the pattern transversely and at right angles to the vertical line 14. To form the pocket so that it will be breast conforming in shape or substantially pyramidal, the pattern is cut along line 14 to a point slightly below line 13, as indicated at 15, thus providing an edge 16 for zone 10 and an edge 17 for zone 11. Zones 10 and 11 thus become flaps 10 and 11. Flap 10 is then overlapped on flap 11, as indicated by way of example in Fig. 4. The overlap is such, however, that edge 16 lies below the transverse line 13. When this overlap is accomplished, edges 18, 19 and 20 of flap 11 will be in juxtaposition to edges 21, 22 and 23 of flap 10. It is intended in the cutting of the fabric to so form the pocket that the warp and the weft threads of the fabric should parallel dotted lines 14 and 13 respectively, so that transverse stretch in zones 9 and 12 should be at a minimum, while flaps 10 and 11, by being overlapped, will have the threads in bias relationship to the end that transverse stretch is permitted. It has been found advantageous in the forming of the pockets to provide an inwardly extending dart at 24 and 25. The resulting breast pocket formed as aforesaid is substantially straight along the base portion thereof, as indicated for sections 1 and 2 at 26 and 27, while the portion of the breast pocket which receives the shoulder straps may have angularly related edges, as indicated for one of said breast pockets at 28 and 29. The zone of juncture between edges 28 and 29 receives a short length strap 30, which may carry a buckle 31 adapted to adjustably receive the shoulder strap member 32, which strap member has one end secured to the back portion of the brassière.

Edges 16 and 17 in the finished breast pocket are left unsewed to the breast pocket fabric in

order that there may be no interference with the bias stretch. The brassière may be given an edge finish as illustrated in the drawing to enhance its appearance.

The operation, uses and advantages of the invention are as follows:

When the brassière is positioned around the body the edge portions 26 and 27 closely engage the body beneath the breasts, and when the back portions are connected by the means 1 and 8, the brassière will tightly but comfortably engage the body. As the weft and warp threads of a breast pocket are in right angular relationship for the lower portion of the breast pocket, little stretch occurs at this zone, and hence the usual auxiliary body band is unnecessary. As the upper portion of each breast pocket has its fabric on a bias line, transverse stretch to accommodate any fullness of the breasts results. The shoulder straps complete the remaining support, and strength of structure results at the zone of connection of the straps with the breast pockets due to the fact that the fabric is of double thickness at this zone. In other words, the present construction is such as to allow the greatest strength at the zone of greatest tension and support.

A further feature of the present invention resides in the fact that the present brassière is cool to wear. The overlapped portions, by not being seamed along edges 16 and 17, allow a certain amount of circulation at this zone, and by having a single thickness of fabric below the overlapped portions, a comparatively light fabric may be utilized, permitting passage of air therethrough.

I claim:

1. In a brassière, a pair of pocket portions formed of fabric, the lower half of each pocket portion having its warp and weft threads running transversely of and vertically relative to the lower edge of said pocket portion, and the top half of said pocket portion divided into equal halves with the halves superimposed so that they completely overlap to place the fabric on a bias, and thereby permit stretch in this portion of the pocket.

2. A method of forming a fabric breast pocket for a brassière which consists in providing a fabric piece of irregular outline, slitting the fabric parallel to a thread line to substantially the transverse center of said pocket, to thereby provide two flaps, and thereafter completely overlapping

said flaps substantially 90 degrees to place the fabric thereof on a bias and whereby the fabric is fashioned into breast receiving contour.

3. A method of forming a fabric breast pocket for a brassière which consists in providing a fabric piece of irregular outline, slitting the fabric parallel to a thread line to substantially the transverse center of said pocket, to thereby provide two flaps, and thereafter completely overlapping said flaps substantially 90 degrees to place the fabric thereof on a bias and whereby the fabric is fashioned into breast receiving contour; followed by sewing the overlapped edges of said flaps together, the edge of the fabric adjacent the slit being unsecured.

4. In a brassière, a pair of joined sections, each section including a breast pocket and a back member, together with means for detachably securing the back members together; each breast pocket divided into upper and lower halves, the upper half divided into equal halves to provide a pair of flaps in completely overlapped relationship of substantially 90 degrees to give a bias effect and to permit stretch of this portion of the pocket, the lower portion of said pocket being substantially non-stretchable.

5. In a brassière, a pair of joined sections, each section including a breast pocket and a back member, together with means for detachably securing the back members together; each breast pocket divided into upper and lower halves, the upper half divided into equal halves to provide a pair of flaps in completely overlapped relationship of substantially 90 degrees to give a bias effect and to permit stretch of this portion of the pocket, the lower portion of said pocket being substantially non-stretchable, said overlapped edges of the flaps being secured together, and one edge of each flap being unsecured.
